UNITED STATES PATENT OFFICE.

DAVID J. BESSE, OF SAN ANGELO, TEXAS.

AIR COOLER.

Application filed March 16, 1927. Serial No. 175,780.

This invention relates to means adapted to lower the temperature of living rooms for comfort, or of compartments for preserving food, and consists of a frame over which is draped a loosely woven fabric, means for supplying water to the fabric to keep the same moist, a fan for creating a positive circulation of air whereby the moisture is evaporated and the air cooled, and 10 a float controlled pump for elevating and supplying the water to the reservoir into which the fabric dips and from which it derives the moisture.

While the drawings illustrate a preferred embodiment of the invention, it is to be understood that in adapting the means to meet specific needs and requirements, the design may be varied and such other changes in the minor details of construction may 20 be resorted to within the scope of the invention as claimed, without departing from the spirit thereof.

For a full understanding of the invention and the merits thereof, reference is to be had to the following description and the drawings hereto attached, in which,—

Figure 1 is a vertical, central, longitudinal sectional view of an air cooler, embodying the invention.

Figure 2 is a detail view of a portion thereof showing more clearly the float controlled pump.

Figure 3 is a vertical, transverse sectional view of the cooler.

Figure 4 is a detail view showing more clearly the float controlled switch, whereby the circuit of the motor provided for operating the pump is closed and opened.

Corresponding and like parts are referred to in the following description and designated in the several views of the drawings by like reference characters.

The numeral 1 designates a suitable framework which may be of any open construction and dimensions depending upon the particular adaptation and use of the invention. A reservoir 2 is located at the top of the framework and is open at the top and closed at its bottom and sides, so as to hold a quantity of water. An ice box 3 is located within the reservoir 2 and is adapted to receive ice, for cooling the water of the reservoir. A loosely woven fabric 4, or fine wire mesh, is draped over the framework and hangs along opposite sides thereof, as indicated most clearly in Figure 3.

This fabric dips into the reservoir 2 and lies against the bottom and sides thereof, as indicated most clearly in Figure 3. The fabric 4 draws the water from the reservoir 60 2 and is kept in a moist condition so long as the reservoir contains a supply of water. Troughs 5 are provided at opposite sides of the framework for the lower ends of the fabric 4 to enter and discharge surplus 65 moisture. A stiffening and reinforcing strip 6 is applied to the lower end of each side portion of the fabric to hold the same in proper position and prevent displacement of the lower ends from the troughs and thereby assure the drippings discharging into the 70 said troughs.

A tank 7 is disposed to receive the drippings from the trough and when necessary water from any source may be supplied to 75 the tank 7. A pump 8 is associated with the tank 7 so as to draw the water therefrom and discharge it by way of a pipe 9 into the reservoir 2. An electric motor 10 is provided for operating the pump 8 and current 80 is adapted to be supplied thereto from a suitable source, the circuit including a switch which is adapted to be automatically operated by means of a float 11 to make and break the circuit. The switch includes a 85 contact 12 and a member 13, the latter being pivoted intermediate its ends to a post 14, or other convenient support. A stem 15 projecting from the float 11 is provided with spaced stops 16 and 17 which are adapted 90 to alternately engage the member 13 so as to make and break the circuit, whereby the motor 10 is controlled for operating the pump 8.

An electric fan 18 is disposed to create 95 a positive circulation of air, whereby to evaporate the moisture from the fabric 4, consequently reducing the temperature of the air which may be utilized for cooling and ventilating purposes in living apartments or storage chambers for feed to preserve the same. The fan 18 may be of any make adapted to be electrically operated and is suitably mounted upon the framework 1 between the hanging portions 4 of the 100 fabric.

The box 3 is double walled and inverted and rests with its open side in contact with the bottom of the reservoir 2. The air space enclosed between the walls of the box retains 110 the cold and prevents the rapid melting of the ice which is placed upon the bottom of

the reservoir or trough 2 and is enclosed by the box which receives the same.

The term fabric is used to include any woven material, such as textile, or wire, and 5 of a nature to hold water in a film which by evaporation cools the air. The device may be used in any place where the air is required to be cooled, such as hospitals, sick rooms, and places of public assemblage, including 10 halls, churches, theatres, hotels and the like.

Having thus described the invention, I claim:

An air cooler including a framework of 15 open construction, a reservoir at the top of the framework to receive water and ice, troughs at opposite sides of the framework

adjacent the bottom thereof, a fabric dipping into the reservoir and extending along opposite sides of the framework and having 20 its lower end terminating in the troughs, a tank disposed below the troughs to receive the drippings therefrom, a pump for drawing water from the tank and dispensing it into the reservoir, float controlled means actuated by the change of level of the water 25 in the tank to throw the pump into and out of action, and a fan disposed below the reservoir and between the depending portions of fabric to create a positive circulation of 30 air.

In testimony whereof I affix my signature.

DAVID J. BESSE. [L. S.]
